UNITED STATES PATENT OFFICE.

JAMES M. HOPKINS, OF FROSTVILLE, ARKANSAS, ASSIGNOR OF ONE-HALF TO
LEE WALLACE.

CAR-COUPING.

SPECIFICATION forming part of Letters Patent No. 662,359, dated November 20, 1900.

Application filed June 13, 1900. Serial No. 20,209. (No model.)

To all whom it may concern:

Be it known that I, JAMES M. HOPKINS, a citizen of the United States, residing at Frostville, in the county of Lafayette, State of Arkansas, have invented certain new and useful Improvements in Car-Couplers; and I do hereby declare the following to be a full, clear, and exact description of the invention, such as will enable others skilled in the art to which it appertains to make and use the same.

My invention relates to car-couplers; and one object is to provide a device of this nature which shall be self-locking and which may be unlocked from the platform of the car.

15 A further object is to provide a construction which shall be cheap of manufacture as well as perfect in operation.

With these objects in view I have constructed a device of this nature such as is described in this specification and shown in the accompanying drawings, in which—

Figure 1 is a perspective view of my invention. Fig. 2 is a sectional line XX of Fig. 1. Fig. 3 is a horizontal section; and Fig. 4 is an elevation of the open end of the draw-head, showing a portion in section.

By referring now to the drawings, my invention comprises a draw-bar 2, having a draw-head 2 formed thereupon. As seen in Fig. 3, a partition 3 extends into the draw-head, thereby dividing it into two compartments 4 and 5. The compartment 5 is considerably the larger of the two, and at its outer edge is pivoted a knuckle 6, which is substantially U-shaped. The link 6 may swing freely upon its pivot 7, and when it is in its locked position, as shown in dotted lines in Fig. 3, its inner edge rests against the extremity of the projection 3 and a stop 8, which extends into the compartment 5 for this purpose, and adjacent the stop 8 is a helical spring 8^a, which bears at one end upon the wall of the compartment 5 and at the other end upon the rear side of the jaw 6^b of the knuckle 6. This spring will hold the link normally in an open position, as shown in solid lines in Fig. 3. The compartment 4 has substantially parallel walls, as shown in Figs. 3 and 4, and this compartment contains a locking-dog 9. The dog 9 is somewhat elongated and one of its ends is adapted to extend beyond the projection 3, as shown in Fig. 2, and it is pro-

vided with an upwardly-directed arm 10, which extends above the draw-head and into the box 11, mounted thereon. The upper end 55 of the arm 10 is slotted, as shown in Fig. 2, and through the slotted portion passes a shaft 12, which is secured at its ends to the opposite side of the box 11. Also projecting upwardly from the dog 9 is an operating-rod 13, 60 which passes through a perforated lug 14, and a helical spring 15 is disposed upon the operating-rod 13, one of its ends being seated upon the dog 9, while its other end bears against the under side of the lug 14. 65

The operation of my invention is as follows: Assuming that two cars to be coupled are provided with couplers made in accordance with my invention and that the parts of my coupler are in the position shown in solid 70 lines in Fig. 2 and in dotted lines in Fig. 3, the two cars are brought together and the jaw 6^a of each coupler engages the jaw 6^b of the opposite coupler. This will force the last-named jaws against the outer ends of the 75 dogs 9, which will move them rearwardly into their compartments. When the jaws 6^b have reached the position shown in the dotted lines in Fig. 3, the dogs 9 will be returned to their normal position by means of the spring 15, 80 and when in this position they will lie against the extremities of the jaws 6^b and will prevent pivotal movement of the knuckles. From this it will be seen that it will be impossible for the two cars to be drawn apart, 85 as when this is attempted the ends of the jaws 6^b will bear upon the ends of the dogs 9, and as these will be forced against the outer wall of the compartment 4 it will be impossible for the jaws to swing upon their pivots. 90 When it is desired to uncouple the two cars, the operating-rod 13 is raised. This will raise the dog 9, and when the lower limit of the slot in the arm 10 has reached the shaft 12 the dog will be clear of the lower wall of 95 the draw-head, and it will then swing rearwardly and be drawn out of engagement with the end of the jaw 6^b. The cars may then be drawn apart, and when this is done the links 6 will swing upon their pivots and their jaws 100 6^a will become disengaged. The operating-rod 13 may then be released, and when this is done the spring 15 will cause the dog to resume its normal position, as shown in Fig.

2. The operation of coupling the cars may then be repeated.

It will be readily seen that I may make my invention of any suitable material and that 5 I may make slight alterations in the construction herein shown and described without departing materially from the spirit of my invention.

Having now fully explained the invention, 10 what I claim is—

In a car-coupler the combination with a head having a partition dividing it into compartments, of a stop in one of the compartments, a knuckle comprising angularly-disposed jaws and pivoted in said compartment with the stop, said knuckle being adapted to be moved to cause one of its jaws to lie against the stop and partition, a spring disposed against the knuckle and the inner wall 15 of the head to hold the knuckle yieldably projected, a bodily-movable dog adapted for movement into and out of the path of move-

ment of the jaw that contacts with the partition and stop to alternately lock and release the knuckle, a box upon the head and having a perforated lug therein, a shifting-rod passed through the box and lug and engaged with the dog for moving it, a helical spring disposed upon the rod and resting with its ends against the dog and lug to hold the dog normally and yieldably in its locking position, an arm extending upwardly from the dog and into the box and having its upper end slotted, and a pin engaged with the box and the slot of the arm for limiting the movement of the dog. 30

In testimony whereof I sign my name, in the presence of two subscribing witnesses, on this 14th day of May, 1900.

JAMES M. HOPKINS.
